UNITED STATES PATENT OFFICE.

CLEAVER W. WAGNER, OF DANVILLE, PENNSYLVANIA

SELF-WINDING CLOCK.

No. 909,485.

Specification of Letters Patent.

Patented Jan. 12, 1909.

Application filed April 30, 1908. Serial No. 430,216.

To all whom it may concern:

Be it known that I, CLEAVER W. WAGNER, of Danville, in the county of Montour and State of Pennsylvania, have invented a certain new and useful Improvement in Self-Winding Clocks, and do hereby declare that the following is a full, clear, and exact description thereof, reference being had to the accompanying drawings, in which—

- 10 Figure 1 is a view partly in vertical section and partly in elevation of a clock embodying my invention, the parts being shown in the positions they occupy immediately after the completion of the winding operation; Fig. 2
15 a similar view of but a portion of the clock showing the position of the parts at the instant of the closing of the circuit immediately previous to the winding operation; Fig. 3 a detail view in section on the line 3—3 of Fig. 20 2; and Fig. 4 a detail view in perspective of the center arbor arm and the armature arm.

My invention relates to electrically operated self-winding clocks in which a circuit is periodically closed by the running down of 25 the motor spring in order that a magnet may be energized to automatically place the motor spring under stress or tension to continue the operation of the clock, and my invention more particularly relates to the arrangement of the circuit and the circuit closing and opening devices, to the end that the 30 number of parts of the mechanism may be reduced so as both to cheapen the cost of manufacture and render the operation of the 35 clock certain or reliable.

As the time train of the clock which I have selected to illustrate an embodiment of my invention is of ordinary construction, no description of it is necessary beyond stating 40 that it is supported by two metal frame plates 10, preferably of brass, which are secured to an iron base 11, by which the clock movement is supported in a suitable casing. The motor spring which I prefer to employ is 45 a helical spring 12 which at one end is secured to one of the usual frame connecting bolts or posts, and at its other end is attached to an arm 13, which at one end is loosely pivoted on the center arbor 14 of the time train so 50 that it may be turned on such arbor independently thereof in one direction, and which carries a pawl 15 that engages a ratchet wheel 16 mounted on the center arbor, so that the pull of the spring is made effective to rotate 55 the center arbor, and thus to actuate the time train. The loose connection between

the arm 13 and the arbor, by which the arm may be moved in one direction independently of the arbor, is for the purpose of enabling the stretching of the spring, or the placing of it under increased tension, by such movement of the arm 13. This movement of the arm to automatically place the spring under stress or tension is produced by the engagement with the under side thereof of an arm 65 17 which is attached to and projects from an armature 18 of an electro-magnet 19 which is attached to and supported in a vertical position with its pole pieces uppermost, by the 70 frame base 11.

The armature is pivotally supported by means of a rock shaft 20 that is journaled at its opposite ends in arms or brackets 21 attached to the respective frame plates so that when the magnet is energized, the armature 75 will rock downward and its arm 17 will rock upward, and engaging the under side of the arm 13 will swing the latter upward, causing the pawl 15 thereof to slip backward over the teeth of the ratchet wheel, and lengthening the motor spring, the arm being retained at the point to which it is moved by the engagement of the pawl with a ratchet tooth, and such engagement of the pawl and the ratchet tooth being the means by which the 80 power of the spring is transmitted to the center arbor and thus to the time train. The engaging surfaces of the two arms 13 and 17, as is common in this art, and in numerous other arts, are convexedly rounded, so as, in 85 effect, to constitute the engaging surfaces of two gear teeth.

I utilize the armature arm 17 as one terminal, or make it one of the contacts of the circuit by which the magnet is energized and deenergized, and I utilize the arbor supported arm 13 as the other terminal, or constitute it the other contact, and by this means, I not only reduce the number of parts of the mechanism, but avoid the use of delicate 95 parts apt to be easily deranged, for said two arms can be made comparatively heavy, and I get comparatively extended and good surfaces for electrical contact. It is, of course, necessary to automatically break the circuit 100 when the limit of movement of the spring by means of the armature is reached, and I accomplish this in a very simple manner, merely by providing the extremity of the armature arm 17 with a covering of insulating 105 material 22, which when the arbor-supported arm 13 is raised to the desired extent, constituting

tutes the sole contact between the two arms, and thereby breaks the circuit, and the magnet being de-energized, the armature is released. The armature when released is rocked upward and its arm rocked downward by means of a flat spring 23 which at one end is secured between the armature arm 17 and the armature rock shaft 20 and at its other end bears against the under side of a block 24 of insulating material on a post that is fastened to one of the frame plates, and which block constitutes a stop to limit the downward movement of the armature arm by being engaged thereby. The block 24 is used because it is supported from one of the frame plates and I utilize the latter as a part of the circuit. For this purpose one terminal of the winding of the electro-magnet is electrically connected to said frame plate, the other terminal thereof being connected by an insulated wire to a binding post 25 which is attached to a bar or strip 26 of non-conducting fiber or other insulating material, which is secured to one of the frame plates, and by means of which binding post an electrical connection is made with one pole of the battery or other source of electrical energy. The other pole of the battery is connected to a binding post 27 which is also attached to the strip 26 of insulating material, and from said binding post 27 a flexible conductor 28 extends and is attached by a socket 29 electrically to the arbor-supported arm 13.

35 A body of suitable insulating material 30 is interposed between the arm 13 and the center arbor, in order to insulate said arm from the clock frame. To supplement the contact between the arms 13 and 17, I preferably attach to the arbor-supported arm 13, an elastic or spring finger 31 which has one end free and normally projected beyond the under surface of the arm 13, so that said spring will first engage the armature arm 17, and bearing yieldingly but firmly against the armature arm will make good electrical contact therewith, and the contacting surfaces will be kept bright by slight movement of the spring over the arm surface which I provide for, that is produced by the action of the armature arm against the spring.

40 The operation of my clock is as follows: Assuming the motor spring to be fully stretched, and the magnet de-energized by the breaking of the circuit, the spring will draw the arbor-supported arm 13 downward, thereby operating the time train, and when said arm is lowered to a point where the finger 31 touches the armature arm 13, the circuit will be closed through the magnet and the armature being attracted by the latter, its arm 17 will be lifted, and first pressing upward the spring finger 31, the armature arm will engage the arbor-supported arm and 45 will move the latter upward, placing the mo-

tor spring under increased tension, which upward movement will continue until the insulating surface on the end of the armature arm is the only portion of the armature arm which has contact with the arbor-supported arm 13, whereupon the circuit will be broken and the magnet de-energized. When the circuit is closed, its course, starting with the binding post 25, will be from the latter through the magnet coils, thence to the base 11 and 50 through the frame plates and the arms 21 to the armature rock shaft 20, which is preferably of brass, thence to the armature arm 17, also preferably of brass, to the arbor-supported arm 13, and from the latter by the 55 flexible conductor cord 28 to the binding post 27.

It will be observed that the only pivots through which the current must pass are the journals of the armature rock shaft, and as 60 these can be made comparatively large, there are always sufficient surfaces in contact to afford an unimpeded path for the current, so that I utilize the frame as a portion of the circuit free from any practical disadvantage. 65 The parts of my circuit closing and opening mechanism are few, and they can readily be given ample strength, and their operation is certain. The winding or placing of the spring under tension takes place without any 70 interference whatever with the running of the clock.

Having thus described my invention, what I claim is—

1. In a self-winding clock, the combination of an electro-magnet, its armature, an arm carried by the armature, forming a part of the magnet circuit, a motor spring, a second arm connected therewith also forming a part of the magnet circuit, said arms directly 105 engaging each other and constituting electrical contacts for closing and opening the circuit, and a yielding finger carried by one of the arms and co-acting with the other.

2. In a self-winding clock, the combination of a clock movement, comprising a train and frame plates, a motor spring, an arm pivoted to and insulated from one of the arbors to which said spring is connected, an electro-magnet having an electrical connection with 110 the frame, an armature, a rock shaft for the armature pivoted to said frame and having electrical connection therewith, an arm carried by the armature and having electrical connection with said rock shaft, said two 115 arms being located so that one may engage the other, and one of said arms having a portion of its engaging surface of insulating material.

In testimony that I claim the foregoing, I 120 have hereunto set my hand.

CLEAVER W. WAGNER.
